RECEPTACLE FOR FROZEN PRODUCTS

Filed Feb. 1, 1930

FIG. 2

FIG. 1-1
William R. Willauer.

By: Charles M. Mills Attest.

UNITED STATES PATENT OFFICE

WILLIAM R. WILLAUER, OF PHILADELPHIA, PENNSYLVANIA, ASSIGNOR TO MARATHON PAPER MILLS COMPANY, OF ROTHSCHILD, WISCONSIN, A CORPORATION OF WISCONSIN

RECEPTACLE FOR FROZEN PRODUCTS

Application filed February 1, 1930. Serial No. 425,228.

This invention relates to a receptacle for frozen products, such as, ice-cream or the like, and more particularly to a receptacle for refrigerating such products during transportation or storage.

My invention, in its broadest aspect, contemplates the use of a double-walled container for frozen products and a tube for a solidified gaseous refrigerant centrally positioned in the container, the tube and container being interconnected so as to provide for a circulation of the refrigerating medium after conversion to the gaseous state through the space between the double walls of the container to thus completely surround the frozen products with said medium.

It is accordingly an object of this invention to provide a refrigerating receptacle for frozen products wherein a solid refrigerant that is normally gaseous is employed and wherein the receptacle is so constructed as to provide for the insulation of the same by means of such refrigerant when converted into the gaseous state.

It is a further object of this invention to provide a refrigerating receptacle for ice-cream and the like whereby such products may be efficiently and readily transported and stored without a substantial change in their physical form.

Other and further important objects of this invention will become apparent from the following description and appended claims.

Referring now to the drawing which discloses a preferred form of my invention:

Figure 1 is an isometric view of my receptacle, parts thereof being shown in section and,

Figure 2 is a detail in isometric of a portion of the paper board plies forming the end members of said receptacle.

The improved receptacle of this invention indicated generally by the reference numeral 1, comprises a container 2, of sulfurized fiber board or the like, for the frozen products. The ends of the container 2 are closed by friction closures 3 and 4, each of which have a flange 5 for gripping the ends of said container. The closure members 3 and 4 are also made of sulfurized fiber board.

The inner face of each closure 3 and 4 is provided near its center with a cup-shaped member or socket 6, secured thereto by means of brads or similar conventional fastening means 7. An inwardly extending flange 8 on said members 6 fits about and frictionally grips the open ends of a tubular refrigerant receptacle 9 to thereby close the ends of said tube and support the same in said container 1. The tube 9 is adapted to be filled with a solidified gaseous refrigerant, such as solid carbon dioxide or the like. The socket members 6 and end members 3 and 4 are provided with communicating openings or passages 10 for a purpose to be later described.

Surrounding the frozen products container 2, is a jacket or casing 11, said jacket being composed of a plurality of plies of corrugated fiber board 12 and 13, as clearly shown in the section C in the lefthand side of Fig. 1. Each ply of said fiber board comprises a wall 14 having a corrugated sheet 15 secured thereto, so that when the plies are assembled to form a jacket as shown in Fig. 1, the spacing provided by the corrugated sheets 15 will form open ended passages extending the full length of the jacket 11. The ends of jacket 11 are closed by means of end disks 16 and 17 which fit against the end members of container 2. Said end disks are secured to the jacket 11 by means of strips 18 of sealing paper or the like.

The end disks 16 and 17 are also constructed of a plurality of plies of corrugated fiber board in the same manner as the plies forming the body portion of jacket 11. When the end disks are secured on the jacket 11, the passages occurring in the main body portion of the jacket between the container 2 and the wall 14 of the outer ply of the jacket will overlie the corrugated sheet 21 of the inner ply 20 of said end disks. Said corrugated sheets 21 are perforated as shown at 26 in Fig. 2 as is each of the walls 22 of the inner plies 20. The interior of tube 9, by means of the apertures 10 in the sockets 6 and perforations 26 in the corrugated sheets 21 and walls 22 of the jacket end members is thus placed in communication with the above described passages in the jacket body 11 so that when the solidified

carbon dioxide in tube 9 takes up heat from the frozen products in container 2, and is converted to a gas, the gas will circulate from said tube 9, to and through the bottom disk, of the jacket 11, through the jacket 11 and into the top end disk of said jacket. In this way the container 2 and its enclosed frozen products will be completely surrounded by said gas, which is in itself an insulator, and thereby greatly increase the refrigerating efficiency of the receptacle.

In assembling the device, it is merely necessary to roll a pair of plies of corrugated fiber board over the container 2, to form the jacket 11. The lower end disk is then placed on said jacket and secured thereto. The container 2 is then filled with frozen products and tube 13 with a stick of solidified carbon dioxide. The cover 3 is then placed over the container 2 and the upper end disk over the jacket 11.

The device so formed will comprise in effect a container composed of spaced apart walls, the space between the walls containing an insulating gas.

By constructing the device in this manner the gas space required to retain the carbon dioxide is materially reduced. Furthermore, the efficiency of the refrigerant is augmented by producing the lowest temperature of the frozen products at the center of the same.

It has been calculated by employing my device, that at the average summer heat of 75° F. a five gallon can of ice-cream, leaving the storage room at 0° F. will be retained at approximately that temperature for a period of eighteen hours.

It is, of course, to be understood that details of my construction may be varied without departing from the spirit of the invention disclosed and, hence, I do not purpose to limit myself except as is necessitated by the prior art.

I claim as my invention:

1. A refrigerating device for frozen products comprising a container having spaced apart side and end walls with a gas space between said spaced walls, a tube for a solidified gaseous refrigerant centrally positioned in said container and extending the full length thereof, said tube and gas space being interconnected whereby said refrigerant when converted to the gaseous state will circulate from said tube into said gas space.

2. A receptacle for frozen products comprising a container for said frozen products, a tube for a solidified gaseous refrigerant positioned centrally in said container, means for closing said container and tube, a jacket surrounding said container, said jacket being formed of a plurality of plies of corrugated fiber board arranged one on the other to provide gas passages in said plies, said tube and gas passages being interconnected whereby said solidified refrigerant when converted to

the gaseous state will circulate from said tube into said passages.

3. A device for refrigerating frozen products comprising a container for said products, end closures for said container, sockets secured to the inner faces of said end closures, a tube for a solidified gaseous refrigerant supported in and having its ends closed by said sockets, a jacket surrounding said container body, said jacket being formed of a pair of plies of corrugated fiber board arranged to provide gas passages extending the length of said jacket, end disks for closing said jacket, said end disks being formed of a pair of plies of corrugated fiber board arranged to provide a passage communicating with said first passages, said container closures and sockets being perforated to place said tube in communication with the passages in said jacket end disks and body.

4. A device for storing frozen products comprising a double-walled container for said products having a gas space between said double walls, a tube for a solidified gaseous refrigerant centrally located in said container, means for closing the upper end of said container and tube, a double-walled bottom member for closing the lower end of said container and supporting and closing said tube, said bottom member having openings in its inner wall leading to said receptacle and to the gas space between the walls of said container whereby to provide for the circulation of the gas of said refrigerant about said frozen products.

5. A receptacle for frozen products, comprising a double-walled container for said products having a gas space between said walls, double walled top and bottom members for said container, a tube in said container extending the full length thereof so as to be closed by said top and bottom container members, said tube containing a solid gaseous refrigerant, the inner wall of the top and bottom container members being perforated at points overlying and underlying the ends of said tube and the space between the container walls whereby to provide for a circulation of the gas of said refrigerant about the enclosed frozen products.

6. As a new article, a package for frozen products comprising a double walled container, a frozen product in said container, a tube positioned centrally in said container and extending the full length thereof, said tube containing a solid gaseous refrigerating medium, double walled bottom and top members closing the ends of said tube and container, the inner wall of said members having openings therein leading to said tube and the space between said container walls whereby to provide for the circulation of said refrigerant about said frozen product.

7. A refrigerating device for frozen products comprising a cylindrical container hav-

ing spaced apart side and end walls with a gas space between said spaced walls, a tube for a solidified gaseous refrigerant centrally and axially positioned in said container and 5 extending the full length thereof, said tube and gas space being interconnected whereby said refrigerant when converted to the gaseous state will circulate from said tube into said gas space.

10 In testimony whereof I have hereunto subscribed my name at Spartanburg, Spartanburg County, South Carolina.
